A technical line drawing of a circular component, likely a bearing or seal. The outer ring is labeled with the number 1 at the bottom left. Inside the ring, a central hub is labeled with the number 10 at the top left. A large, thick, curved line labeled '17' spans the width of the hub. A small, thin, curved line labeled '15' is located at the bottom of the hub. The inner ring is labeled with the number 14 at the bottom right. The entire assembly is labeled with the number '18' at the top right. Various other numbers are scattered around the perimeter of the outer ring, including 2, 3, 5, 6, 7, 9, 12, 13, 16, and 19.

UNITED STATES PATENT OFFICE

2,031,624

THERMOMETER

Albert E. Whittier, Bristol, Conn.

Application March 12, 1935, Serial No. 10,613

2 Claims. (Cl. 73—118)

This invention relates to thermometers of the mechanical class, that is, thermometers in which the temperature indicating means is actuated by a coiled thermo-responsive metallic strip.

5 The object of the invention is the provision of a simple, compact, sensitive, and accurate thermometer of the class mentioned which will show individual degree readings in large figures and that is particularly adapted for application 10 to the doors and walls of stove and range ovens which are heated by gas, coal, oil or electricity, but that is also capable of use in other locations.

This object is attained by arranging the temperature indicating figures on a rotatably mounted cylinder that encircles a coil of thermostatic metal, one end of the coil being attached to the cylinder and the other end of the coil being adjustably fastened to a member which is fixed in an enclosing case that in front of the cylinder 20 has a window designed to expose but one temperature reading at a time.

In the accompanying drawing the invention is illustrated as designed for an oven thermometer.

Fig. 1 shows a front view of the thermometer. 25 Fig. 2 shows a rear view with a part of the case removed.

Fig. 3 shows a section on the plane indicated by the dotted line 3—3 on Fig. 2.

Fig. 4 shows a section on the plane indicated 30 by the dotted line 4—4 on Fig. 2.

Fig. 5 shows a section on the plane indicated by the dotted line 5—5 on Fig. 2.

The enclosing case of the oven thermometer shown comprises a threaded shell 1 which is open 35 at both ends and that has an external flange 2 and internal flange 3 at the front end, and a threaded shell 4 which has a closed rear end and an external flange 5 at its front end, the former shell being adapted to be thrust into an opening 40 in a wall or panel and the latter shell to be screwed upon the former shell in such manner that the wall or panel will be clamped between the external flanges of the shells.

In the front end of the shell 1 is a disk 6 that 45 has a window 7 and in the construction illustrated this disk has ears 8, 9, bent in from diametrically opposite edges. These ears are perforated and support a freely rotatable spindle 10. Rotatably mounted on the spindle near the ear 8 is a collar 50 11. Extending in from and fastened to the ear

9 is a hub 12. Rotatably mounted upon this hub but designed to be fastened thereto by a screw 13 is a collar 14. A cylindrical member 15 upon which temperature indicating figures or lettering are arranged so as to read longitudinally of the axis of the cylinder, is fastened by screws 16 to the rotatable collar 11. One end of a strip 17 of thermostatic metal coiled within the cylindrical member is fastened by a screw 18 to the collar 11. The other end of the thermostatic coil 10 is fastened by a screw 19 to the collar 14. By loosening the screw 13 and turning the collar 14 the tension of the coil may be adjusted for the purpose of calibrating the elements in order that the figures will show the correct temperature 15 through the window 7 in the shell.

With the active elements properly calibrated figures showing the correct temperature to which the thermometer is subjected will be seen through the window in the closure. But one temperature 20 reading at a time is exposed through this window. Owing to the length of the coil of thermo-responsive metal which is arranged in a small space in this structure, extended angular movements 25 of the cylinder are attained as the temperature changes. This permits close calibration and allows the figures to be so large that they may be quickly read without effort or close inspection.

The invention claimed is:—

1. A thermometer comprising a shell that is 30 open at both ends, a removable disk closing one end of said shell, said disk having a window, a cylindrical member rotatable in the shell and carrying temperature indications adapted to be exposed through said window, and a coil of 35 thermo-responsive metal with one end connected to said disk and the other end connected to the cylindrical member.

2. A thermometer comprising a shell, a disk 40 with a window at one end of the shell, said disk having inwardly extending ears, a spindle loosely supported by said ears, a cylindrical member rotatably mounted in the shell upon said spindle and carrying temperature indications adapted to be exposed through said window, and a coil 45 of thermo-responsive metal with one end fixed with relation to the shell and the other end attached to said cylindrical member.
